UNITED STATES PATENT OFFICE.

WILLIAM KAHL, OF BROOKLYN, NEW YORK.

TOWEL RACK.

Application filed June 4, 1921. Serial No. 474,924.

To all whom it may concern:

Be it known that I, WILLIAM KAHL, a citizen of the United States, and a resident of the borough of Brooklyn, county of 5 Kings, city and State of New York, have invented certain new and useful Improvements in Towel Racks, of which the following is a specification.

This invention relates to towel racks.

10 Among the objects of the present invention it is aimed to provide a towel rack that may be conveniently and expeditiously attached in place, without the use of nails or such like fastening means. The present invention more particularly takes advantage, 15 of the heat generated by the hot water boilers present in the average kitchen, and of the support afforded by the tubing extending from such boiler for the rack so that 20 towels supported by a rack so secured to a boiler and suspending therefrom in proximity to the boiler may be quickly dried on account of the aid afforded by the heat so generated.

25 Specifically, the invention contemplates a towel rack having a metal bracket to which are pivotally secured a plurality of rods, so that their ends will co-operate with one another to automatically limit the extent of 30 swing of the rods, to afford a support facilitating the pivoting of the several rods at the same level, and furthermore to afford a rigid support capable of carrying comparatively heavy loads.

35 The invention still further contemplates a novel arrangement and selection of the parts of a rack which takes advantage of the position of a boiler and the appurtenant tubing, and the increased rigidity afforded 40 when bending certain metal parts, so as to obtain a maximum efficiency with a minimum number of parts and minimum amount of material.

45 These and other features, capabilities and advantages of the invention will appear from the subjoined detail description of one specific embodiment thereof illustrated in the accompanying drawing in which.

50 Figure 1 is a fragmental side elevation showing a boiler and a towel rack secured thereto; and Fig. 2 is a plan of the same.

Fig. 3 is a perspective fragmental view showing the towel rack in detail.

55 In the embodiment illustrated, there is provided a boiler 10 of usual construction having tubing such as the nipple 11 extend-

ing from the upper end thereof with the usual polygonal faced nut 12 formed thereon. To this nipple 11 in the present instance, the bracket of the towel rack is attached. It is obvious that tubing extending from other portions of the boiler may also be used to advantage for so supporting the towel rack.

The towel rack itself comprises essentially 65 a bracket 13 to which are pivotally secured a plurality of rods, in the present instance, the wooden rods 14, 15 and 16. The bracket 13 is preferably composed of sheet metal a part 70 of which is bent into the resilient U-shaped yoke member 17, in the parallel limbs of which, alining openings 18 and 19 are formed to receive the screw 20. The openings 18 or 19 are used according to the size 75 of nipple, nut or tubing to which the bracket may be secured, it being understood that the yoke 17 will encircle the nipple as shown in Fig. 1 and the limbs thereof drawn tight by means of the screw 20 and nut 21. One 80 of the limbs of the yoke 17 continues into an enlarged flat shell or support 22 bent at an angle relative to the limbs of the yoke 17 and preferably having a plurality of ears, three being shown in the present instance, as at 23, 24 and 25 to be received by the 85 slots, formed by the bifurcated ends of the rods 14, 15 and 16 respectively. The rods 14, 15 and 16 in the present instance are pivotally secured to such ears 23, 24 and 25 by 90 means of the pivot pins 26, 27 and 28. The rods, 14, 15 and 16 in the present instance are round wooden rods of the type usual 95 with towel racks of the swinging type.

From the foregoing it will be seen that the rods will swing from the same level, made 95 possible by the flat support 22, and will so extend from the boiler 10 that the towels may conveniently hang adjacent to the boiler thereby to facilitate the drying of the same.

As shown in Fig. 3 the ends of the rods 14, 15 and 16 so contact relative to one another that the opposing rods 14 and 16 will be limited in their movement by abutting against the end of the rod 15. The rod 15 will be limited in its lateral movement by 100 contacting and engaging with the rods 14 or 16.

From the foregoing it will also be seen 110 that neither nails nor such like fastening means are required, and that the towel rack can be conveniently and quickly secured in place even by the most unskilled.

The bracket 13 is composed of a single piece of sheet metal and may be conveniently stamped out by a single operation thus serving materially to maintain the cost of manufacture at a minimum.

It is obvious that various changes and modifications may be made to the details of construction without departing from the general spirit of the invention as set forth 10 in the appended claims.

I claim:

1. A towel rack comprising a bracket and towel supporting rods, the bracket having a horizontal shell, a plurality of ears extending 15 from said shell, the ends of the supporting rods being slotted to receive said ears, and pivot pins for pivotally connecting the slotted ends of the rods to said ears, the ends of the rods overlapping one another so as to form stops to limit the outward swing 20 of the rods.

2. The combination with a plurality of towel supporting rods, of a one-piece sheet

metal blank stamped into a yoke arm and a supporting shell, the yoke arm being bent 25 into a U-shaped support engaging resilient yoke and the shell being bent at right angles to said yoke, the ends of said rods engaging said shell, and pivot pins for pivotally connecting the ends of said rods to said shell. 30

3. The combination with a plurality of wooden towel supporting rods, of a one-piece sheet metal bracket having a support engaging resilient yoke and a supporting shell, the shell being bent at right angles to 35 said yoke, a plurality of ears extending from said shell, the ends of the supporting rods being slotted to receive said ears, and pivot pins for pivotally connecting the slotted ends to said ears. 40

This specification signed and witnessed this fifth day of May, 1921.

WILLIAM KAHL.
